JAR OR BOTTLE CLOSURE

Albert J. Hadert, Fort Wayne, Ind.

Application September 28, 1945, Serial No. 619,153

4 Claims. (Cl. 215—71)

1

The object of the present invention is to provide a novel and improved type of sealing means for jars or bottles but more particularly for bottles. It is a well known fact that there are many beverages sold in bottles, which become "flat" or stale if left opened and unused for any appreciable length of time. Among these are such beverages as carbonated soft drinks, beer, and the like. Many attempts have been made to provide closures for bottles of this sort intended to be placed in closed position after the first drink or glass of the beverage is removed from the bottle to prevent the liquid from becoming "flat" as described.

The object of my invention is to provide an improved type of stopper for this purpose, so constructed that it may be operated by the same hand which holds the bottle. Thus, it is not necessary for a person having the freshly filled glass in one hand and the bottle in the other, to set the glass down and use two hands to place the stopper or closure upon the bottle. I accomplish this result by providing a closure of such a nature that it may, in effect, be rolled over the edge of the neck of the bottle to the closed position, or from closed position to open position, by the same hand which holds the bottle. I further provide a closure of such a nature as to have a multiplicity of seats so that the same portion of the closure does not contact with the bottle neck upon every occasion of use.

Among the other advantages of the invention is that when applied to the bottle it remains in place until the contents of the bottle are exhausted; no adjustments have to be made and no clasps or like devices have to be operated. An especially important feature of the invention is that when the closure is in open position the mouth of the bottle is entirely unrestricted and full flow of the beverage therefrom may be had.

It is well known in the bottling art that many economies can be effected if the public can be persuaded to use larger containers and fewer of them. Some brewers have attempted to market beer in quart containers. One of the reasons that the public has been slow in purchasing these containers is that much beer goes to waste by becoming "flat" because it cannot be effectively sealed after being opened and thus becomes "flat" before it can be used. The use of the device of the present invention will encourage the use of larger containers because of the convenience with which the above-recited objections are eliminated.

Referring to the accompanying drawings, constituting a part of this application:

2

Figure 1 is a side elevation of the invention.

Figure 2 is a plan view of the structure of Figure 1.

5 Figure 3 is a perspective view of the bottle embracing element, hereinafter described, employed in the construction illustrated in Figures 1 and 2.

Figure 4 is a sectional view through a spherical closure cap hereinafter described; and

10 Figure 5 is a plan view of the structure illustrated in Figure 4.

I call the device of this invention the "flip-flop" bottle closure because of the ease with which a spherical stopper or closure 22 may be flipped from the full line to the dotted line position of Figure 1 or may be flipped from the dotted line to the full line position of said figure.

The primary reason for this easy action is that the spherical or circular nature of the closure permits it to roll over the edge of the bottle mouth 20 and be drawn into sealing position by the action of springs hereinafter described.

As the spherical closure I may use a ball made completely of rubber, artificial rubber, or any other suitable material of such elasticity as to

25 make a fluid-tight joint between itself and the bottle mouth under the action of the springs or I may make the body of the ball of a hard material, such as wood, hard rubber, any hard plastic or the like, as indicated in Figure 4. Here I have

30 illustrated the body 5a of the ball as being of such a hard material and having a channel 5b about its periphery which receives a rubber or other elastic band 5c. In this case the hard body 5a is provided with headed studs 5e adapted

35 to be engaged by the outer ends of the springs 18. An advantage arising from the use of the partly hard, partly soft ball is that for a given spring strength the ball makes a better seal where the force exerted can be concentrated on the rubber band area instead of being dissipated over the

40 whole volume of a whole rubber ball.

In carrying out the invention I provide a saddle 15 of the shape illustrated in perspective in Figure 45 3 is employed. This saddle comprises a semi-circular band 16 having protuberances 17 which bear against the side of the bottle neck. Wire loop springs 18 having the large convolutions 19

45 and the smaller convolutions 19a are pivoted at 20 to the saddle 15 and at their outer ends have 50 pivotal engagement with the studs 21 of ball closure 22. At its upper forward corners the saddle of Figure 3 carries inturned lugs 23 which bear against the bottle neck immediately below the top flange thereof. Stop ears 24 carried by

55 the saddle limit the upward throw of the springs

18, and thus prevent the ball from passing over on to the wrong side of the bottle. By providing stops to limit the throw of the ball so that it can never move over to the left side of the bottle, in Fig. 1, a clear pouring zone is maintained at that side of the bottle mouth. The ball is never permitted to come into the path of the poured liquids and the clear zone side of the bottle neck is never contacted by a ball which, otherwise, might have had sticky residues of drinks, thereon. The ball 22 may be moved to and from bottle sealing position with a rolling action which permits of its being manipulated with one hand. No external fastening device other than the springs 18 themselves need be employed in holding this structure in position upon the bottle, the tension of the springs serving the function of holding the saddle in place in both open and closed positions of the ball.

Many ways will readily suggest themselves to those skilled in the art for modifying the disclosed structure. However, as far as I am aware, I am the first to provide a closure of this nature embodying a closure element of circular form so that any point in its periphery may constitute a sealing surface with respect to the mouth of the bottle and so that it may be moved from closed to open position with a rolling movement over the edge of the bottle neck. Springs of the type described have a particular utility when mounted so that one end is journalled with respect to the ball while the other end is journalled or pivoted at 20 upon the saddle because springs of this type differ from ordinary helical springs in that while they are wound in the direction of their pull they are more or less rigid laterally. Therefore when a person, using only one hand, thrusts with the thumb against the ball to close the bottle, the force of the thrust is all expended in useful effort, that is in rolling the ball over the edge of the bottle neck to closed position. If the springs were ordinary helical springs, the thumb thrust, necessarily exerted more from one side than the other, would tend to thrust the ball bodily laterally and out of alignment with the bottle mouth. But with the springs wound to resist lateral displacement while permitting a pull of the ball into the bottle mouth, the thumb thrust is utilized to best advantage. It is this which yields the flip-flop action and makes possible the very easy manipulation of the closure without requiring the operator to set his drink down and use two hands to seal the bottle to prevent the remainder of the contents from going stale.

Therefore, I wish it to be understood that the invention is not limited to the precise construction set forth but that it includes within its purview whatever changes fairly come within the terms or the spirit of the appended claims.

Having described my invention, what I claim is:

1. In a closure for a bottle of the type having a neck and an open mouth at the top of said neck, a laterally removable saddle shaped to fit upon the neck of the bottle, a ball constituting a closure for the mouth of the bottle supporting means by which the ball is carried, which constitute a horizontal axis of rotation for said ball, and a pair of springs, one at each side of the saddle, said springs each comprising an inner and an outer end portion, the inner end portions of

the springs being pivotally connected to the saddle and the outer end portions of the springs being connected to the supporting means which constitute the axis of rotation of the ball, the said end portions of each spring being connected by a relatively large and a smaller convolution, both convolutions being integral with each other and with the end portions and both convolutions comprising substantially a complete ring and both of said convolutions being wound about axes substantially parallel to the horizontal axis of rotation of the ball.

2. A closure for a bottle as recited in claim 1 in combination with stop means carried by the saddle and lying in the path of said springs in a position to limit the movement of the ball to prevent its overthrow materially beyond seating position.

3. A closure for a bottle as recited in claim 1 wherein the major portion of said ball is of hard material, said ball being provided with a circumferential channel and a band of elastic material in said channel, said band being constructed and arranged to rest upon and close the open mouth of the bottle when the ball is in closed position.

4. In a closure for a bottle of the type having a neck, an open mouth at the top of the neck and an outstanding flange around the top of said neck, a laterally removable saddle shaped to fit upon the neck of the bottle, a ball constituting a closure for the mouth of the bottle, supporting means by which the ball is carried, which constitute a horizontal axis of rotation for said ball, and a pair of springs, one at each side of the saddle, said springs each comprising an inner and an outer end portion, the inner end portions of the springs being pivotally connected to the saddle and the outer end portions of the springs being connected to the supporting means which constitute the axis of rotation of the ball, the said end portions of each spring being connected by a relatively large and a smaller convolution, both convolutions being integral with each other and with the end portions and both convolutions comprising substantially a complete ring and both of said convolutions being wound about axes substantially parallel to the horizontal axis of rotation of the ball, inwardly extending ears upon the saddle which engage beneath said flange of the bottle, and outwardly projecting stops upon the saddle in the path of movement of the springs which limit the throw of the springs and ball in the direction of closing, beyond the closed position of the ball.
